UNITED STATES PATENT OFFICE.

ALBERT D. BENNETT, OF CLEVELAND, OHIO.

PUZZLE.

No. 845,845.

Specification of Letters Patent.

Patented March 5, 1907.

Application filed May 18, 1906. Serial No. 317,551.

To all whom it may concern:

Be it known that I, ALBERT D. BENNETT, a citizen of the United States, residing at Cleveland, in the county of Cuyahoga and State of Ohio, have invented new and useful Improvements in Puzzles, of which the following is a specification.

This invention is a puzzle, and comprises a box provided with a transparent top and containing a number of fixed pegs and loose pieces which when placed or assembled on the pegs in a certain order form a complete design or figure.

In the accompanying drawing, Figure 1 is a plan view of the invention. Fig. 2 is a plan view showing the puzzle solved. Fig. 3 is a central vertical section.

Referring specifically to the drawing, 5 denotes a box of any desired shape, having a transparent or glass top 6. On the inside of the box are a number of vertical pegs or pins 7, which are fixed to the bottom of the box. The box also contains a number of loose pieces 8, each of which has a perforation 9, whereby the pieces may be placed on the pegs, the puzzle being to first disarrange the pieces and then place or assemble them on the pegs in a certain order, so as to form a complete design or figure. This is done by proper manipulation of the box, which requires considerable skill and ingenuity, thereby making the puzzle interesting and entertaining.

In the drawing I have shown a number of pieces representing a dismembered human figure, said pieces when placed on the pegs in proper order making a complete figure; but other figures, such as various animals, may be used without departing from the scope of the invention.

I claim—

1. A puzzle comprising a base, a series of fixed pins rising therefrom, and a series of perforated movable pieces adapted to be selectively mounted on said pins.

2. A puzzle comprising a base, a series of fixed pins rising therefrom, and a series of movable pieces representing a dismembered figure inside of the casing, and adapted to be selectively mounted on said pins to form a complete figure.

3. A puzzle comprising a casing having a transparent cover, a series of fixed pins rising from the floor of the casing, and a series of movable pieces inside the casing, and adapted to be selectively mounted on said pins.

In testimony whereof I have signed my name to this specification in the presence of two subscribing witnesses.

ALBERT D. BENNETT.
